UNITED STATES PATENT OFFICE

THURE J. MAGNUSON, OF CHICAGO, ILLINOIS, ASSIGNOR TO THE FANNER MANUFACTURING COMPANY, OF CLEVELAND, OHIO, A CORPORATION OF OHIO

CHAPLET

Application filed May 13, 1932. Serial No. 611,149.

This invention relates to an improvement in foundrymen's chaplets, one of its objects being to provide the industry with a chaplet having a head formed in such a way that the sand will readily pack in on both sides, eliminating voids and unpacked spaces which have hitherto interfered with the firm seating of chaplets. Thus the invention aims to eliminate the need for tucking the sand around the head. To the accomplishment of the foregoing and related ends, said invention, then, consists of the means hereinafter fully described and particularly pointed out in the claims.

15 The annexed drawing and the following description set forth in detail certain structure embodying the invention, such disclosed means constituting, however, but one of various structural forms in which the principle 20 of my invention may be used.

In the drawing Figs. 1 and 2 are respective views of chaplets embodying the improved head but having different forms of stem; Figs. 3 and 4 are side elevations partly in section 25 corresponding to Figs. 1 and 2 respectively; Fig. 5 is a plan view of the heads shown in Figs. 1 and 2; Fig. 6 is a plan view of a modified form of head; and Fig. 7 is a plan view of a further modification.

30 Referring to the drawing, it will be seen that the chaplet consists of a head 1 and a stem 2 or 3 provided with such nicks, collars and/or other irregularities and roughnesses as may be useful for holding the upper end 4 or 5 of the stem in the casting and at the same time allowing the lower end, carrying the head, to be broken off readily. The stem as such is not a feature of the present invention.

In the prior art the head 1 has usually been 35 square and of sufficient area to afford a good bearing but difficulties have been found in that the sand did not pack or shape around the edges of the head. In order to eliminate this I have relieved and cut away portions 45 of the edge, as shown at 6 in the various figures, so that the overall dimensions of the head are not reduced and the bearing surface is as wide as though the cuts 6 had not been made. The reduction in area made by the 50 cuts 6 is more than compensated for by the

fact that the sand packs well around the remaining surface of the head and that the bearing is still widely distributed. It will be seen, for example, that the corners 7, 7, are as widely spaced apart as previously so that 55 any overturning tendency is still resisted by a broad base.

The principles of the invention may also be applied to a head such as 10 shown in Fig. 6 in which the relieving openings are entirely 60 included within the periphery of the head instead of cutting into the edge. Thus, in the head 10, openings 11 are cut out through which the sand can work in packing around the head.

A further modification is shown in Fig. 7 in which a head 12 is shown having four openings, such as 13, the outer edge of the head 12 being uncut. In Figs. 5, 6 and 7 the opening into which the stem is fastened is 70 indicated at 14 in each instance.

In operation, the chaplet is placed in the usual manner, the only difference being that the head 1 becomes more firmly embedded in the sand than is usually in case.

75 Other modes of applying the principle of my invention may be employed instead of the one explained, change being made as regards the structure herein disclosed, provided the means stated by any of the following 80 claims or the equivalent of such stated means be employed.

I therefore particularly point out and distinctly claim as my invention:

1. A chaplet having a head comprising a 85 plate inwardly cut away at opposite peripheral points.
2. A chaplet having a head formed by a plate with semi-circular notches cut out of opposite sides thereof.

90 Signed by me this 11 day of May, 1932.

THURE J. MAGNUSON.
